CLAIM

The ornamental design for a face screen for a helmet safety device, as shown and described.

DESCRIPTION

FIG. 1 is a left side perspective view of a face screen for a helmet safety device showing my new design, the helmet shown in broken lines is for illustrative purposes only and forms no part of the claimed design;

FIG. 2 is a right side perspective view thereof;

FIG. 3 is a top plan view thereof;

FIG. 4 is a side elevation view thereof;

FIG. 5 is a front elevation view thereof; and,

FIG. 6 is a rear elevation view thereof.
